SLINGSHOT FRAME

Albert P. Gaud, 701 NE. 7th Ave.,
Fort Lauderdale, Fla. 33304

Filed Mar. 20, 1972, Ser. No. 236,560

Term of patent 14 years

Int. Cl. D21—01

U.S. Cl. D34—15 YY

FIG. 2

FIG. 1

FIG. 6

FIG. 4

FIG. 3

FIG. 1 is a front elevational view of a slingshot frame showing my new design, the rear being identical:

FIG. 2 is a top plan view thereof;

FIG. 3 is a bottom plan view thereof;

FIG. 4 is a side elevational view thereof;

FIG. 5 is a section view of prong thereof;

FIG. 6 is a section view of shaft thereof.

I claim:

The ornamental design for a slingshot frame, substantially as shown and described.
